UNITED STATES PATENT OFFICE.

HAROLD ROWNTREE, OF CHICAGO, ILLINOIS, ASSIGNOR TO NATIONAL PNEUMATIC COMPANY, OF CHICAGO, ILLINOIS, A CORPORATION OF WEST VIRGINIA.

INCLOSURE-FRAME FOR ELEVATOR-HATCHWAYS.

1,180,320.

Specification of Letters Patent.

Patented Apr. 25, 1916.

Application filed March 8, 1912. Serial No. 682,524.

To all whom it may concern:

Be it known that I, HAROLD ROWNTREE, a citizen of the United States, residing at Chicago, county of Cook, State of Illinois, have made a certain new and useful Invention in Inclosure-Frames for Elevator-Hatchways, of which the following is a specification.

This invention relates to inclosure frames for elevator hatchways.

The object of the invention is to simplify and improve the construction of elevator hatchway framing, to render the same more economical to manufacture, and to increase 15 the strength and rigidity of frame work of this class and nature.

Other objects of the invention will appear more fully hereinafter.

The invention consists substantially in the 20 construction, combination, location, and relative arrangement of parts, all as will be more fully hereinafter set forth, as shown in the accompanying drawings, and finally pointed out in the appended claims.

25 Referring to the accompanying drawings, and to the various views and reference signs appearing thereon,—Figure 1 is a view in front elevation of an elevator hatch framing embodying the principles of my invention. Fig. 2 is a horizontal view in section on the line 2, 2, Fig. 1, looking in the direction of the arrows. Fig. 3 is a vertical section on the line 3, 3, Fig. 1, looking in the direction of the arrows.

35 The same part is designated by the same reference sign wherever it occurs throughout the several views.

In carrying out my invention I propose to 40 employ sheet metal posts and to arrange the same vertically on opposite sides of the elevator hatchway door. I also propose to employ longitudinally extending sheet metal members designed to be arranged above the doorway of the hatch, and the vertical posts, 45 the panel member over the doorway and suitable corner pieces, all made of sheet metal, suitably stamped out, and rigidly secured together at their abutting edges by welding or otherwise. By forming these 50 various parts of sheet metal I am enabled to produce an exceedingly strong and durable frame work which is very simply constructed, easily put together and economical to manufacture. I am also enabled to im- 55 part to the frame work any desired panel-

ing, ornamentation or configuration, which may be stamped into the sheet metal members at the time they are stamped out, thereby presenting or providing an exceedingly ornamental appearance to the entire framework.

In the drawings A, represents vertical posts formed of sheet metal, preferably stamped out into U-shape in cross section. These posts are respectively arranged on opposite sides of the hatch doorway. Immediately above the hatch doorway is a longitudinally extending sheet metal member G. At their adjacent ends the vertical posts A, and the horizontal members G, are securely fastened together by means of panel members or corner pieces B. A convenient and economical method of connecting together the horizontal and vertical members A, G, and the corner panels B, is to weld them together at their meeting edges. Said parts being made of sheet metal this is easily and readily accomplished. In order to extend the framing from the upper edge of the door upwardly to the ceiling L of the floor above, I propose to employ similar vertically arranged sheet metal posts C, and at the top a similar horizontal member E, that is, similar, respectively to the vertical posts A, and to the horizontal members G, and to secure these members, C, E, the vertical posts C, and the horizontal members E, together by similar corner panels D, said vertical posts C, being also welded or otherwise secured to the corner panels B. All of these members A, G, C, E, and the corner pieces or panels B, D, may be suitably stamped out of sheet metal. They may also be paneled or given any desired ornamentation in the stamping process. And they may be similarly secured rigidly together by welding them all into one integral rigid frame work. In order to fill up the space between the vertical members C and the horizontal members E, G, a panel F, may be employed which may also be of sheet metal and given any desired ornamentation or paneling, and also rigidly secured at its edges, by welding, or otherwise, to the edges of the adjacent members C, G, E.

A construction of frame work for elevator hatchways embodying the principles of my invention may be employed in connection with any suitable form of arrangement of doors. In the particular form shown, the

doors are indicated at J, and are of the folding leaf or panel form of doors, two panels being arranged on each side of the vertical center line of the hatch doorway and these 5 folding leaves or panel members fold or swing toward the side posts or members A, in opening. It is to be understood, however, that my invention is not to be limited or restricted in respect to the particular form or arrangement of doors employed.

10 In practice I prefer to form the horizontal members G, directly above the doorways to form boxes or inclosures within which may be conveniently located the operating mechanism by which the hatchway doors J, may be operated or moved or otherwise actuated to their open or closed positions. Where such operating mechanism is employed I propose to use a shield or cover plate H, for 15 the rear of the box member G, as shown in full and dotted lines in Fig. 3. This hinged member or cover plate H, forms a door which covers and incloses the actuating mechanism within the U-shaped panel member G.

20 It will be observed that the inner surface of the various panels and members are arranged in vertical line with each other. (see particularly Fig. 3.) This aligned inner surface should also be in vertical line with the inner surface of the doors, when the latter are closed, thereby presenting a smooth, unobstructed inner wall or surface for the hatchway in which travels the elevator car, 25 indicated at K. This vertically flush or aligned inner surface of the panels and doors, when the latter are closed, should also be in vertical line with the end surface or edge of the flooring above and below each landing, 30 as clearly indicated in the drawing. This arrangement affords a smooth surface within which the elevated car moves thereby avoiding shoulders or ledges which are dangerous to passengers, and avoids the liability of 35 accidents or injury to passengers being caught between the edge of the floor of the car and a projecting edge of the hatchway framing, door supporting apparatus, or the 40 floor of the landings.

45 From the foregoing description it will be seen that I provide an exceedingly simple elevator hatchway frame work which is capable of being economically constructed, and packed for shipment, readily assembled, 50 and erected, and when erected, which is exceedingly rigid and strong, while at the same time being capable of being given any suitable or desired ornamentation. In practice the various members or parts may be 55 produced in quantity, and of any length, and then cut off to the desired length to accommodate the measurements of any particular flooring or landing space. This very 60 materially reduces the cost of construction and erection of the framework. The corner

65 bracket B, may also be made up and carried in stock.

A construction embodying the principles and features above described is not only simple and economically manufactured but 70 may be packed in knock down condition and transported and shipped at small expense and quickly and easily erected at the point where required.

75 While I have described my invention as employing sheet metal parts for the framing it is to be understood that in its broadest scope, as defined in the claims, my invention is not to be limited or restricted to the use of sheet metal parts, as any other form 80 of metal or weldable material may be employed. The essential feature is the production of a framework made up of different component parts which are welded together to form one rigid structure thereby avoiding the objections of the method heretofore employed of securing the component parts together by screws which are liable to work loose and have to be continually tightened 85 up. This advantage applies whether the 90 frame work forms a complete closure, or is made up of grille or open work patterns. Moreover, the various component parts of the complete framework may be manufactured in standard sections or lengths and 95 cut to the desired length for use in any particular situation, and welded together for erection, whether made of sheet metal or any other form of metal or weldable material. Nor is it necessary for all the 100 component parts of any particular framework to be of the same kind of material. For instance, some of the parts may be sheet metal, while others are of cast or other form of metal. Again, some of the parts 105 shown and described may be entirely dispensed with. Thus, the corner plates B, D, may be omitted and the vertical parts A and C, made in one piece to extend throughout the entire height required, and suitably 110 ornamented as may be desired, and similarly, the horizontal sections E, F and G, may be combined into one or more parts, if desired, or the parts B, C, D, may be made integral with the parts A, or with the parts E, F, G, as may be desired. Other 115 variations and changes in details might readily occur to persons skilled in the art and still fall within the spirit and scope of my invention. I do not desire, therefore, to be limited or restricted to the exact details shown and described.

12 Having now set forth the objects and nature of my invention and a construction embodying the principles thereof what I claim as new and useful and of my own invention and desire to secure by Letters Patent of the United States, is:—

1. In an inclosure frame for elevator hatchways having doorways therein, and in

- combination with the ceiling and floor above and below the doorway, posts of sheet metal stampings arranged vertically on opposite sides of the doorway, horizontally arranged 5 members of sheet metal stampings positioned over the doorway and between the same and the ceiling, and corner plates of sheet metal stampings intermediate adjacent ends of said posts and horizontal members, said posts, horizontal members and plates being integrally united and having their inner surfaces in the same 25 vertical plane with each other and with 30 the inner edges of the floor and ceiling below and above the doorway.
- In testimony whereof I have hereunto set my hand in the presence of the subscribing 35 witnesses, on this 20 day of February, A. D., 1912.
2. In an inclosure frame for elevator hatchways having a doorway therein, and in combination with the ceiling and floor above and below the doorway, vertically arranged 20 posts of sheet metal stampings on opposite sides of the doorway, a horizontal
